W. C. BURRICHTER.
DISINFECTING CABINET.
APPLICATION FILED JULY 26, 1910.

992,639.

Patented May 16, 1911.

UNITED STATES PATENT OFFICE.

WILLIAM CASPER BURRICHTER, OF PANORA, IOWA.

DISINFECTING-CABINET.

992,639.

Specification of Letters Patent. Patented May 16, 1911.

Application filed July 26, 1910. Serial No. 573,947.

To all whom it may concern:

Be it known that I, WILLIAM C. BURRICHTER, a citizen of the United States, and a resident of Panora, in the county of Guthrie 5 and State of Iowa, have invented a new and Improved Disinfecting-Cabinet, of which the following is a full, clear, and exact description.

My invention relates to disinfecting cabinets, and it has for its object to provide one which may be manufactured at very little expense, for use by physicians, nurses, manufacturers, druggists, and also by bankers for disinfecting money.

Another object of the invention is to provide means for introducing and removing the disinfecting gas without inconveniencing those who are in charge of the device.

Still other objects of the invention will 20 appear in the following complete description.

In this specification I will describe the preferred form of my invention, it being understood that the scope of the invention is defined in the appended claims.

Reference is to be had to the accompanying drawing forming a part of this specification, in which the figure is a perspective view of the cabinet, a portion being broken 30 away to disclose the interior.

By referring to the drawing, it will be seen that a cabinet is provided with a base 5, a ceiling 6, side walls 7 and a rear wall 8, a plurality of shelves 9 being mounted in 35 the cabinet, these shelves 9 having openings cut therein, to permit the circulation of the gases. The openings in the lower shelf, 10, are commanded by valve members 11, these valve members being disposed under the shelf 10 and being adapted to close the said 40 openings in the same manner that openings in hot-air registers are closed. The valve members 11 are operated by a handle 12, the shank of which projects through an opening 45 in one of the side walls 7. An outlet pipe 13 is provided, having a branch 14 at the top, leading into the cabinet at its upper portion, the bottom of the outlet pipe 13 being connected with the interior of the cabinet 50 net below the plane of the shelf 10. The outlet pipe 13, below the branch 14, is commanded by a valve 15, the branch 14 being also commanded by a similar valve 16. A tray 17 is disposed on the floor of the cabinet, and a tilting cup 18 is disposed in the cabinet above the said tray 17. The tilting

cup 18 has trunnions 19, which are journaled in the walls of the cabinet, one of the trunnions 19 projecting through the wall of the cabinet and being provided with a handle 60 20, by which it may be rotated. A pump 21 is provided, having outlets 23 and 24, the outlet 23 being connected with the interior of the cabinet below the shelf 10, and the outlet 24 being connected with the interior 65 of the cabinet above the said shelf 10. Suitable valves 25 are provided, one for commanding the outlet 24 and one for commanding the outlet 23, with which the outlet 24 70 communicates.

In using the invention, formaldehyde is deposited in the tray 17 and potassium permanganate is deposited in the tilting cup 18. The materials to be disinfected are then disposed on the shelves 9, after which the door 75 is closed. This having been done, the cup 18 is tilted by means of the handle 20, and, after the gas has been given an opportunity to circulate freely in the cabinet, the valves 15 and 16, which have been closed, are 80 opened and air is forced into the cabinet by means of the pump 21. By this means, all the disinfecting gases are driven out by the pump through the outlets 13 and 14. By means of the valve members 11, the gases 85 15 may be prevented from rising above the shelf 10 and may be driven out of the cabinet through the lower terminal of the outlet pipe 13.

Having thus described my invention, I 90 claim as new and desire to secure by Letters Patent:

1. A disinfecting cabinet having a doorway, a door for closing the doorway, a tilting cup supported in, and operable from 95 without, the cabinet, a tray disposed in the cabinet below the tilting cup, an outlet pipe connected with the cabinet, a valve commanding the outlet pipe, and means for forcing air into the cabinet. 100

2. A disinfecting cabinet having a doorway, a door for closing the doorway, a shelf with openings therein, mounted in the cabinet, valve members for closing the openings 105 in the shelf, a member disposed through a wall in the cabinet, secured to the valve members for operating them, a tilting cup supported in the cabinet, below the shelf and operable from without the cabinet, an outlet pipe connected with the cabinet, and a valve 110 commanding the outlet pipe.

3. A disinfecting cabinet having a door-

way, a door for closing the doorway, a shelf with openings therein, mounted in the cabinet, valve members for closing the openings in the shelf, a tilting cup disposed in the cabinet, below the shelf, means for supporting the cup and for tilting it, two outlet communicating means connected with the interior of the cabinet, one disposed above and the other disposed below the said shelf, 10 valves commanding the outlet communicating means, respectively, two inlet com-

municating means, and means for forcing a fluid through the inlet communicating means.

In testimony whereof I have signed my 15 name to this specification in the presence of two subscribing witnesses.

WILLIAM CASPER BURRICHTER.
